M. CRAMER.
PIPE CUTTER.
APPLICATION FILED OCT. 20, 1916.

1,215,121.

Patented Feb. 6, 1917.

UNITED STATES PATENT OFFICE.

MORRIS CRAMER, OF CLEVELAND, OHIO.

PIPE-CUTTER.

1,215,121.

Specification of Letters Patent.

Patented Feb. 6, 1917.

Application filed October 20, 1916. Serial No. 126,782.

To all whom it may concern:

Be it known that I, MORRIS CRAMER, a citizen of the United States, residing at Cleveland, in the county of Cuyahoga and State of Ohio, have invented a certain new and useful Improvement in Pipe-Cutters, of which the following is a full, clear, and exact description, reference being had to the accompanying drawings.

10 This invention relates to pipe cutters, and has for its general object the provision of a simple, efficient pipe cutter which shall cut pipes by removing a portion of the metal in such a way as to avoid leaving burs at the 15 inside or the outside of either of the adjacent severed ends.

In carrying out my invention I use a frame similar to the usual pipe cutter frame, provided with relatively adjustable separated rollers adapted to engage the exterior of various sizes of tubes and permit the cutter frame to revolve about the same. Between the paths of these rollers is carried a cutter adapted to engage and remove from 25 the pipe a narrow strip of metal upon each revolution of the cutter frame, the cutter being urged into engagement with the pipe by any suitable means.

A pipe cutter constructed substantially as 30 above, is shown, described and claimed in my prior application No. 122,621, filed September 28, 1916.

A more specific object of the present invention is to provide a plurality of readily interchangeable cutters, each adapted to be brought into operative position, thereby allowing most convenient replacement of a dulled or broken cutter. To this end I have constructed a series of cutters integral 40 with a single disk, and so arranged as to be given a partial rotation to bring fresh cutters into operative position, and having conveniently operable means for locking the same with any of its cutter teeth in cutting 45 position. Still another object is to so shape individual cutters on this disk that a portion of a cutter adjacent the one in operative position may engage the pipe being severed, to prevent feeding the cutter into the 50 metal too rapidly.

My invention is hereinafter more fully described in connection with the accompanying drawings. Other features of my invention are set out in the description and the essential characteristics are summarized in the 55 claims.

Referring to the drawings, Figure 1 is a side elevation of my pipe cutter; Fig. 2 is an edge elevation of the same; Fig. 3 is an axial section, showing the cutter, its locking and carrying mechanism, and the means for feeding the same into the pipe; Fig. 4 is a detail view of the cutter and its carrier removed; Fig. 5 is a transverse sectional plan taken substantially on a plane indicated by the line 5—5 of Fig. 1.

Referring to the parts by numerals, the frame of my cutter comprises a substantially C-shaped member 10 having an outwardly extending boss 12 provided with internal threads coöperating with a threaded adjusting rod 14, rigidly carrying at its outer end a fluted handle 15 secured to the rod 14 by threads, and a pin extending through the handle and rod, as indicated at 16. At the lower end of this rod is rigidly mounted a head 17 rotatably engaging a substantially cylindrical socket 18 in a vertically slidable rider 20. This rider carries two pairs of rollers 21 and 22, each pair being axially separated, as indicated in Fig. 2, while the rider itself engages laterally extending flanges 23 of the frame. The rider is shown as made in two parts and having grooves embracing these flanges when these two parts are secured together and in position by bolts 24.

Below the rider 20 the frame is bifurcated and provided with suitable bearings for pairs of rollers 25 and 26 mounted similarly to the rollers 21 and 22.

Cutters 30 are shown as integral with a cutter disk 31 rotatably carried on a pin 32 extending through a longitudinally movable carrier 35. This carrier has a deep slot 36 transversely of its upper end, receiving the substantially parallel sides of the disk 31, and below the pin 32 is a locking screw 34, closely fitting the space between adjacent teeth of the cutter disk. This screw 34 slidably engages a slot 36 in the casing, which is surrounded by a raised rib, engaged by the head 37 of this screw, which may be turned to remove and replace the screw as is necessary to present new cutter teeth to the pipe.

It will be seen that as the rollers 25 and 26 are axially separated and each has an individual bearing pin, the cutters 30 may be rotated and vertically moved in the space between these rollers and the bearings, and the screw 34 may have a corresponding movement by reason of the slot 36 in the frame.

The carrier 35 is shown as cylindrical and slidably fitting a bore 40 in a boss 42 at the opposite end of the frame from the boss 12. Within this bore is a compression spring 44 adapted to exert sufficient pressure on this carrier to force the cutter into active engagement with the pipe and cause it to be fed therethrough as the frame is rotated. This spring 44 bears at its upper end against the carrier 35 and at its lower end the pressure is received by a cap 50 threaded onto the boss 42 and shown as provided with a shoulder against which the spring rests. The cutter is prevented from rotating with relation to the frame by reason of finished shoulders 33 at each side of the carrier 35, the bore for this cutter being continued upwardly to provide the maximum amount of bearing for the carrier. The shoulders 33 closely engage the parallel sides of the disk portion 31 of the cutter, thus holding it constantly in proper relation to the pipe, while permitting its rotation and longitudinal movement.

The cutter (shown in detail in Fig. 4), is designed to embody the following advantageous features. Each tooth is adapted to serve as a stop finger, limiting the inward feeding movement of the cutter tooth which is removing metal from the pipe. This operation is illustrated particularly in Fig. 3, where the tooth immediately to the right of the one removing metal is shown as extending into the peripheral groove in the pipe made by the cutting tooth, and, engaging the bottom of the groove, limits the feeding movement and prevents the cutter breaking through the last remaining portion of the metal too quickly.

It will be seen from the edge view in Fig. 5, that the cutter disks may be very conveniently turned from circular disks to form the cross sectional contour of the teeth. The cutter disks may then be mounted on a suitable arbor extending through the central opening, and the notches dividing the peripheral portion of the disks into teeth may be milled by a single mill of the proper shape, advanced progressively across a number of these cutters. The metal may be removed between the teeth while cutting the same, by a tool adapted to form the bottom of the notch in a semi-circular curve. This saves labor, as the bottom portion of any notch is thus adapted to be closely engaged by the locking pin 34, obviating the necessity of providing a series of holes or other devices for locking the cutter disk.

Accordingly, the cutter is not only capable of being readily manufactured, but one tooth serves the function of preventing too rapid feeding of the operating tooth, and is so shaped as to avoid endangering its own cutting edge. This feature of regulating the depth of the cut has the additional value of prolonging the life of each individual cut-

ting tooth. The cutter may be conveniently held in position and its individual cutting teeth are readily interchangeable with relation to the cutting position, while the locking device is easily provided and simple to operate.

In the particular form of pipe cutter frame shown in the drawings, I prefer to provide outwardly extending handles 60 and 61. The handle 60 is threaded into the fluted member 15, the function of which is to provide a convenient means for turning the adjusting rod 14 to move the rollers 21 and 22 toward or away from the rollers 25 and 26, to engage or release a pipe. The handle 61 is shown as threaded into the cap 50 and these two handles provide suitable leverage for causing the rotation of the frame about the pipe.

The cap 50 is shown as provided with an axially threaded opening 62, which may be normally closed by a screw 63, to which access may be gained by removing the handle 61. This set screw provides a removable closure for the opening 62, whereby oil may be placed in the chamber 40, which may be led to the cutter by a suitable passage 65. I have found that under certain conditions oil will feed itself along the carrier 35 and to the cutter, without the provision of any special passage for this purpose.

Having thus described my invention, what I claim is:

1. In a pipe cutter, the combination of a frame adapted to be revolved about a pipe, a cutter disk rotatably carried by the frame and having a plurality of outwardly extending individual cutter teeth, each provided with a cutting point and a depth-limiting heel, means for locking the cutter disk in various positions, and means for holding the pipe in position for the point of one cutting tool to enter the stock of the pipe and the heel of the next tool to engage the stock of the pipe within the path of the tool which is cutting.

2. The combination with a pipe cutter frame adapted to embrace and be revolved about a pipe, of a cutting tool having a plurality of individual cutting edges, means for movably carrying the tool whereby each of the several edges may be presented to the pipe, means for locking the cutter in any of said positions, and means for feeding the cutter into the pipe.

3. In a pipe cutter, the combination of a frame, means carried by the frame for revolvably embracing the pipe, a cutting tool carried by the frame comprising a rotatable member having a plurality of outwardly projecting cutting teeth, means for locking said cutter in position to present any one of said teeth to a pipe embraced by an embracing means.

4. In a pipe cutter, the combination of a

- frame adapted to revolve about a pipe, a member rotatably carried by the frame and having a plurality of separated alined cutting teeth, means for locking the cutter in position to present any one of said teeth to the pipe, said teeth being so arranged that a tooth adjacent the cutting tooth may engage the pipe to prevent too rapid feeding of the cutting tooth.
- 5 5. In a device of the character described, the combination with a pipe-embracing means, a plurality of separated individual cutters, a member rigidly carrying each of said cutters and movable to present each 10 cutter to the pipe, said cutters being so arranged that when one of them is cutting a portion of an adjacent cutter remote from its cutting edge may bear against the metal operated upon just ahead of the tool which 15 is cutting.
6. The combination with a pipe cutter frame adapted to be revolved about a pipe, a movable member carried thereby and having a plurality of separated alined cutting 20 teeth, means for locking said member into position to present each of said teeth to the pipe, each of said cutting elements having a raised heel portion adapted to engage the metal being operated upon just ahead of the 25 operating cutting element, and spring actuated means carrying said cutter member.
7. The combination with a pipe cutter frame adapted to be revolved about a pipe, a movable member carried thereby and having a plurality of separated alined cutting 30 teeth, means for locking said member into position to present each of said teeth to the pipe, each of said cutting elements having a raised heel portion adapted to engage the 35 metal being operated upon just ahead of the operating cutting element, a longitudinally movable carrier for the cutters, and a compression spring for urging the same toward the pipe.
- 40 8. The combination with a pipe cutter frame adapted to be revolved about a pipe, a cutter disk carried thereby and having a 45 plurality of outwardly extending individual cutter teeth, a carrier embracing said disk and permitting its rotation, means for urging the carrier and cutter toward the pipe, and a locking element extending into said member between adjacent teeth thereby locking it in position to present one of its teeth to the pipe.
- 50 9. The combination with a pipe cutter frame adapted to be revolved about a pipe, a cutter disk carried thereby and having a plurality of outwardly extending individual cutter teeth, a carrier embracing said disk and permitting its rotation, means for urging the carrier and cutter toward the pipe, and a screw extending into said carrier and closely engaging the space between said teeth.
- 55 10. In a pipe cutter, the combination with a frame adapted to be revolved about a pipe, a cutter member carried thereby and comprising a substantially flat disk having a series of outwardly extending cutting elements formed in its periphery, said elements being separated by notches of uniform shape, a carrier embracing said cutter, means revolubly attaching the cutter thereto, means for moving the carrier and cutter toward the pipe, a screw having a shank adapted to fit said notches and having threads engaging the carrier and extending outside the frame and having a head at the exterior of the frame, whereby it may be removed to permit turning the cutter.
- 60 11. The combination with a pipe cutter frame, a plurality of pairs of axially separated rollers carried by the frame and adapted to run in laterally separated paths about a pipe, a cutter having a plurality of individual cutting elements and movable to present any of said elements to the pipe, means for locking the cutter in position with any one of said elements active, and means for urging said cutter toward the pipe.

In testimony whereof, I hereunto affix my signature.

MORRIS CRAMER.
